SEALING TIP FOR WELL CASINGS

Roy Jaswell, Smithfield, R. I.

Application July 19, 1944, Serial No. 545,665

1 Claim. (Cl. 166—10)

1 My invention relates to improvements in well casings, particularly for those of the artesian well type although it is obvious that it may be employed in other types of wells.

An object of my invention is to provide a sealing tip for well casings which may be detachably secured to the lower end of the pipe casing and one which will positively shut off surface water, contaminated water, salt, sand and clay from upper levels from seeping into the well near the upper end of the rock stratum to affect the quality of the water or other liquid being upwards in the well casing.

A further object of my invention is to provide a device of this description which will positively seal off such impurities from the liquid being welled.

These and such other objects of my invention as may hereinafter appear will be best understood from a description of an embodiment thereof of such as is shown in the accompanying drawing.

In the drawings, Fig. 1 is a side elevation partially broken away of my improved sealing tip for well casings.

Fig. 2 is a diagrammatic view showing in elevation my improved sealing tip detachably secured to the lower end of a well casing and showing adjacent strata of the earth's surface around the well hole in diagrammatic section.

In the drawings, wherein like characters of reference generally indicate like parts throughout, 10 generally indicates a sealing tip for well casings constructed in accordance with my invention.

As stated, my invention is particularly adapted for use with artesian water wells. In drilling an artesian well of this type, the hole 12 is first drilled with a churn drill of a larger diameter than the well casing 14 usually about two inches larger. As the hole is being initially driven, a pipe of the diameter of the size of the drilled hole is simultaneously forced down the well hole 12 as the hole is made and the material from the well is bailed out. After the hole 12 is drilled, a well casing 14 of smaller diameter than the first pipe usually of about two inches smaller diameter is inserted into well hole 12 to leave a peripheral space of one inch around the casing.

As it is impossible to insert the large pipe through the rock, a hole without a pipe is drilled through the rock 16 thus providing the rough edges 18 on the portion of the hole 12 within the rock stratum. I have shown in the drawings, a surface ground stratum 20, a gravel stratum 22, a sand stratum 24, and a rock stratum 16 which

terminates above the water stratum 26. The smaller well casing 14 terminates near the upper surface of the solid bed-rock stratum 16, and my invention as stated, comprises a sealing tip 10 for the lower end of the well casing 14 adapted to project within the hole 12 in the rock stratum 16.

My invention comprises a short pipe section 30 or tip for said well casing having an upper end 32 adapted to be detachably secured to the lower end 34 of the pipe casing, in the embodiment shown, the upper end of the tip being threaded as at 36 for this purpose, and the lower end of the well casing 14 being threaded as at 38 for this purpose and an internally threaded coupling ring 40 is provided to detachably couple the threaded upper end of my improved sealing tip 32 to the lower end 34 of the pipe casing 14. I employ the short pipe section 30 in order that my improved sealing member may be readily permanently rigidly secured to the well casing to act as a positive seal to prevent the higher impurities exterior of the well casing from coming into contact with the lower liquid being welled.

I provide an annular resilient sealing member constructed of any suitable relatively soft material such as rubber, synthetic rubber, gutta percha, synthetic resin, or otherwise, comprising the sleeve 42 of substantial height permanently rigidly secured to the outer surface 44 of the lower end of the pipe section 30 and having resilient sealing flanges or rings 46 projecting integrally radially outwardly from said sleeve, said rings 46 being preferably axially spaced from each other substantial amounts as in the preferred embodiment shown and preferably constructed triangular in section so that each may terminate in an annular sealing ridge 48, said rings 46 being preferably spaced axially from each other amounts 50 substantially the radial height 52 of the rings 46. Then if the tip 30 on the lower end of the casing 14 is inserted within the hole 12, which hole as stated is often provided in drilling 45 with an irregular rough surface 18, it is obvious that certain of the rings 46 will completely fill up the indentations 54 in said surface 18 and that where a projection 56 from said surface abuts a ring 46 it may flatten it entirely against a flat 50 land 50 intermediate said rings 46 as at 58 as shown in Fig. 2. It is thus obvious that certain rings 46 so fit in the depressions 54 and that other rings 46 are so flattened by the projections 56 to bear against the resilient lands 50 that a positive resilient seal will be provided so that surface

water, contaminated water, salt, sand, or clay will not seep down through the drilled hole exterior of said casing 14 through to the liquid being welled in the well casing. As shown, my improved seal comes within the upper end of the hole 18 and the rock stratum 16 completely obstructing all downward passage of any fluid between the casing tip 30 and surface 18 of said rock 16 thus positively cutting off all possible downward seepage into the liquid being welled.

If desired, the sleeve 42 may be omitted and the resilient rings vulcanized or otherwise secured to the pipe section 30 at the desired spaced intervals forming the lands 50 on said pipe section between them. With this construction, as the surface against which a rock projection may abut is not resilient, not quite such an efficient seal is provided.

It is apparent therefore that I provide the novel type of sealing tip for well casings with the advantages described above.

It is understood that my invention is not limited to the specific embodiment shown and described and that various deviations may be made therefrom without departing from the spirit and scope of the appended claim.

What I claim is:

A sealing tip for use on well casings for sealing holes in bed rock, comprising a short pipe

section having an externally threaded upper end adapted to be detachably coupled to the threaded lower end of the pipe casing and an annular resilient rubber sealing member comprising a cylindrical sleeve of substantial height permanently rigidly secured throughout its length to the outer surface of the lower end of the pipe section having resilient rubber sealing flanges triangular in section to terminate in annular sealing ridges projecting integrally radially outwardly from said sleeve, said flanges being spaced axially from each other distances at least substantially the radial height of the flanges.

ROY JASWELL.
